(57) CLAIM

The ornamental design for double glider, as shown and described.

DESCRIPTION

FIG. 1 is a side perspective view of the double glider showing our new design;

FIG. 2 is a side elevational view the opposite side being a mirror image;

FIG. 3 is a rear elevational view the front elevational view being a mirror image;

FIG. 4 is a top plan view; and,

FIG. 5 is a bottom plan view.

The broken lines showing of the table and the top slats of the gliders are for illustrative purposes only and form no part of the claimed design.
